SLIDABLE SIDE JAW WRENCH

Archie T. Allen, Hickman, Calif.

Application July 29, 1949, Serial No. 107,579

2 Claims. (Cl. 81—165)

1

My invention relates to wrenches of the adjustable jaw type having means at the end of the handle for actuation to adjustably set the jaws.

An object of the invention is to provide a wrench of the character described such that a setting of the wrench jaws may be effected either from its handle end or from its head end.

Another object of the invention is to provide a wrench of the character described which is of a particularly simple and effective structure requiring a minimum number of parts.

The invention possesses other objects and features of advantage, some of which, with the foregoing, will be set forth or be apparent in the following description of a typical embodiment thereof and in the accompanying drawings, in which,

Figure 1 is a longitudinal edge view of a wrench embodying my invention.

Figure 2 is a side face view of the wrench.

Figure 3 is a central longitudinal section of the wrench.

Figure 4 is a section taken at the line 4—4 in Figure 3.

Figure 5 is a section taken at the line 5—5 in Figure 2.

The illustrated wrench structure essentially comprises a stock or body 8 providing coterminous head and handle portions 9 and 11 respectively, with the head 9 providing a jaw portion 12 integral therewith and adjustably mounting a jaw member 13 having a jaw portion 14 opposite the jaw 12 for operative cooperation therewith. A base portion 15 of the member 13 slidably and complementarily engages a head slideway 16 which extends as a slot from the forward end face of the head and is continued as an opening at the base of the jaw 12, said slideway being in the central plane of the head. The base portion 15 of the member 13 is of uniform cross-section and comprises a web 15' terminating in a bead 15'' having its diameter greater than the thickness of the web 15' whereby the member 13 is held against lateral escape from the complementary slideway 16.

Inwardly of the slideway 16, the head 9 is provided with a transverse opening 17 therethrough, with its cavity extending along and slightly into the cylindrical portion of the slideway 16 and having mutually parallel side faces 18 and 19 transverse to the slideway. A screw pin 21 is mounted in the head 9 to extend across the opening 17 in substantially parallel relation to the slideway and in perpendicular rela-

2

tion to the cavity faces 18 and 19 and rotatably mounts a member 22 in retained position between said faces. As particularly shown, the screw pin 21 extends into the head from the side edge thereof which is opposite the edge which provides the jaw 12.

A major portion of the member 22 is formed as a worm screw 23 having its thread extending from its end opposite the cavity side 18 and engaging a rack 24 provided on the jaw member 13, said rack having been provided by cross-notching the bead 15'' of the member. The worm 23 of the member 22 extends from the opening 17 at the head sides whereby the member may be manually engaged and rotated to effect adjustments of the jaw 14 with respect to the jaw 12, the member 22 being, by reason of its function, conveniently referred to as a spreader member. In the present structure, the line of the slideway 16 is oblique to the line of the handle 11 whereby the opposed jaw faces are similarly oblique to the handle line.

It will now be noted that the handle portion of the stock 8 is provided with a longitudinal bore 25 which journals a shaft or stem 26 extending from within the opening 17 to a point beyond the handle extremity, and mounts a handle extension portion 27 by which it is arranged to be rotated; as particularly shown, the handle extension 27 is provided with an axial socket 28 which has the extending shaft end releasably fixed therein by means of a setscrew 29. Noting that the handle extension 27 is cylindrical, the handle portion immediately adjacent thereto is also cylindrical and of like size whereby the peripheral faces of the extension and handle are flush at their mutually abutting ends.

The forward end of the shaft 26 mounts a bevel gear 31 which is arranged to be in constant meshing engagement with a bevel gear 32 provided on the end of the spreader member 22 which is nearest the face 19 of the opening 17, the gear 31 being shown as comprising an integral portion of the member. The hub portion of the bevel gear 31 is engaged in a complementarily countersunk end portion of the bore 25 and is pinned to the shaft end which mounts it. The arrangement is essentially such that the handle extension 27 is in swivelled relation to the handle 11.

Forwardly of its rear cylindrical portion the handle 11 is recessed therealong and to the cavity 17 to provide flattened side face portions 33 which intersect an intermediate enlarged portion of the bore 25, and cover plates 34 are fixed

opposite said side face portions of the handle. The plates 34, it is noted, extend forwardly to conceal the gears 31 and 32 while leaving the worm 23 exposed for its manual operation from either or both sides of the head, and the closed space defined at the intermediate enlarged portion of the bore 25 may contain a suitable lubricant grease for the shaft 26.

It is to be particularly noted that the present wrench is arranged for the relative adjustment of its jaws 12 and 14 either by manually turning the spreader member 22 or the handle extension 27, and that said elements are correspondingly rotated together. The arrangement is particularly important to a mechanic by reason of the fact that settings of the wrench jaws may be effected from the most accessible portion of the wrench under various use conditions, it being particularly noted that the control from the handle extension provides for the setting and application of the wrench jaws in spaces where access to the spreader member is prevented.

From the foregoing description taken in connection with the accompanying drawings, the advantages of the present wrench will be readily understood by those skilled in the art to which the invention appertains. While I have described the principle of operation, together with a form of my invention which I now consider to comprise a preferred embodiment thereof, I desire to have it understood that the showing is primarily illustrative, and that such changes and developments may be made, when desired, as fall within the scope of the following claim.

I claim:

1. In a conventional slidable side jaw wrench having a head portion and a handle extended generally right angularly therefrom, said head portion having a transverse opening therethrough, and slidable jaw rotatable actuating means operably connected to the slidable jaw and mounted in the head portion at the opening and accessible for direct manual turning to actuate the slidable jaw, and said handle having an axial bore therethrough in communication with the transverse opening in the head portion, and the

handle having a slot extending therethrough radially from the bore, a shaft journalled in the bore and axially fixed and rotatably supported therein, bevel gears directly connecting the shaft and said means and entirely within the head at the transverse opening therethrough, and a cover plate secured to said handle and enclosing the axial bore and radial slot and extending over a part of the transverse opening in the head portion to enclose the bevel gears, and further means for turning said first named means, including a handle extension fixed to said shaft for direct manual turning thereof.

2. In a conventional slidable side jaw wrench having a head portion and a handle extended generally right angularly therefrom, said head portion having a transverse opening therethrough, and slidable jaw rotatable actuating means operably connected to the slidable jaw and mounted in the head portion at the opening and accessible for direct manual turning to actuate the slidable jaw, and said handle having an axial bore therethrough in communication with the transverse opening in the head portion, and the bore being formed with an enlarged portion radially thereof and opening through the handle, a shaft journalled in the bore and axially fixed and rotatably supported therein, bevel gears of substantially like size directly connecting the shaft and said means and entirely within the head at the transverse opening therethrough, and a cover plate secured to said handle and enclosing the axial bore and the enlarged portion thereof and extending over a part of the transverse opening in the head portion to enclose the bevel gears, and further means for turning said first named means, including a handle extension fixed to said shaft for direct manual turning thereof.

ARCHIE T. ALLEN.
